OPPOSED PISTON ENGINE CONSTRUCTION
WITH REMOVABLE CYLINDERSCarl A. Jacobson, Ardmore, Pa., assignor to The
Baldwin Locomotive Works, a corporation of
Pennsylvania

Application November 15, 1945, Serial No. 628,820

6 Claims. (Cl. 123—51)

1

This invention relates to internal combustion engines and more particularly to the kind of engine in which two pistons are arranged in each cylinder, reciprocating in opposite directions with a common combustion chamber. The pistons act on two separate crankshafts, one at each end of the cylinders, connected by suitable means such as gearing so that they rotate in timed relation to each other.

One object of my invention is to provide an improved combination of elements whereby cylinders may be conveniently removed from or assembled with the engine frame without requiring dismantling of the two crankshafts at each end of the cylinder as well as the many other parts, accessories, devices and the like which are a usual part of engines.

Other objects and advantages will be more apparent to those skilled in the art from the following description of the accompanying drawings in which:

Fig. 1 is a side elevation of my improved engine with one part in section to show details of construction;

Fig. 2 is a transverse section taken on line 2—2 of Fig. 1;

Fig. 3 is a horizontal section taken on line 3—3 of Fig. 1; and

Fig. 4 is a transverse section of a modified arrangement of cylinder.

The engine shown in Fig. 1 is a vertical multi-cylinder opposed piston engine, but the same principles of construction are equally applicable to a horizontally disposed engine, and hence any reference to upper and lower crankshafts is to be considered as applicable to either engine position. The construction is characterized by an upper and a lower crankcase 1 and 2 as shown in Figs. 1 and 2. These crankcases are arranged parallel to each other and contain upper and lower crankshafts 3 and 4 mounted in any suitable number of bearings certain of which are indicated at 3' and 4' and are connected by two end frame sections or columns 5 and 6, both of which are hollow and one of which, such as 5, is used to house a gear train 7 for connecting the two crankshafts and for driving certain usual and well-known accessories and devices (not shown). The other column section 6 would be available for accessory parts if desired.

It may be readily seen that the basic frame is in the form of a rectangle with an open central portion containing engine cylinders 8 whose upper and lower ends are firmly bolted at 9 to the upper and lower crankcases. These cylinders are

thus arranged to be removed or inserted laterally at right angles to the plane of the cylinder axes without dismantling the crankcases and their crankshafts or usual accessories associated therewith, although pistons and connecting rods must be removed, of course. In the case of a horizontal engine, they would be removed in an equivalent vertical manner instead of laterally. If desired, the cylinders may carry the explosion thrust load on the crankshafts tending to separate the latter, although my arrangement is particularly effective in allowing such forces to be taken by cooperative tension plates or members 10 which are welded or otherwise suitably secured to the crankcases. The combustion space as is usual in this type of engine is located between opposed pistons 11 which are provided with connecting rods 12.

In order to remove the cylinders 8, the pistons 11 and connecting rods 12 are first removed through crankcase hand hole openings 13 and 14 after removal of covers therefor.

The engine construction shown may be composed of parts consisting of castings and fabricated sections assembled by well-known methods of bolted joints or by welding into an integral frame unit and as such connecting means do not enter into my present invention they are not further described. Similarly such elements as fuel injectors, water circulating pumps for cooling the engine cylinders, and many other well-known and necessary devices are omitted for clarity.

It will be noted, however, that I obtain a high degree of frame rigidity by preferably forming the inner halves 15 and 16 of the crankcases 1 and 2 as an integral part of the end columns 5 and 6, although these various parts could be formed separately and bolted or welded together, if desired, to form a permanently rigid unitary structure. In this case, only the uppermost and lowermost halves of the crankcases 1 and 2 would be normally removable along parting flanges 17 and 18. In my improved construction the rigidity of this frame unit is further increased by the box-like nature of the end columns 5 and 6 as is clearly shown in Fig. 3. Access to the interior of these columns may be had either through their upper and lower ends or through suitable end plates such as 19, Fig. 3, which in this particular instance closes the opening through which the gear shafts 20 are inserted.

In the modification shown in Fig. 4 one cylinder is illustrated for convenience in a horizontal position and is to be considered for purposes of my invention to be a vertical engine as well. Each cylinder is formed in two halves 8a and 8b

along a transverse division line 22 just to one side of the middle of the combustion chamber. The adjacent ends of the two cylinder halves are suitably secured together by a series of circumferentially disposed bolts 23, it being noted that fuel injectors 24 are located entirely in the longer cylinder half 8b and can accordingly be positioned on the median line of the combustion chamber. This arrangement allows complete lateral removal of both cylinder halves by first removing only the piston 11a and connecting rod 12a through a manhole opening such as 13 or 14, Fig. 1. The piston removal is accomplished by first removing the connecting rod bearing cap and then laterally swinging the lower end of the rod toward the manhole opening while simultaneously lowering the piston out through the bottom of cylinder. The crankshaft is of course rotated to its lowermost position to permit removal of the piston. When the piston 11a is removed the crankshafts may be, or will already have been, rotated to move the other piston 11b clear of the parting line 22 to allow lateral removal of the cylinder half 8a whereupon the other cylinder half 8b may be disconnected from its crankcase and moved axially until it clears piston 11b and thence removed laterally from the engine frame. In this manner it is not necessary to disconnect piston rod 12b although if desired both cylinder halves and both pistons and rods may be removed in the same manner as for the single integral type of cylinder.

It will of course be understood that various changes in details of construction and arrangement of parts may be made by those skilled in the art without departing from the spirit of the invention as set forth in the appended claims.

I claim:

1. The combination in an engine comprising, a frame, having upper and lower crankcase portions and means for rigidly supporting said crankcases in spaced relation to each other, upper and lower crankshafts normally mounted in said crankcases, opposed pistons connected to said crankshafts, cylinders in which said pistons operate with a common combustion chamber therefor, means for removably securing said cylinders to said frame between said crankcases, and said crankcases having lateral clearance adjacent the ends of said cylinders to allow the latter to be laterally removable while both the upper and lower crankshafts remain in their normal position.

2. The combination in an engine comprising, a frame, upper and lower crankshafts normally mounted therein, opposed pistons connected to said crankshafts, cylinders in which said pistons operate with a common combustion chamber therefor, and means whereby said cylinders are supported by said frame and are laterally removable therefrom while both the upper and lower crankshafts remain in their normal position, said frame including upper and lower horizontally extending portions constituting the inner halves of crankcases and end columns rigidly secured to said horizontal frame portions to provide a unitary rectangular shaped structure with the laterally removably cylinders disposed within the interior of said rectangle.

3. The combination in an engine comprising, a frame, upper and lower crankshafts normally mounted therein, opposed pistons connected to said crankshafts, cylinders in which said pistons operate with a common combustion chamber therefor, means whereby said cylinders are sup-

ported by said frame and are laterally removable therefrom while both the upper and lower crankshafts remain in their normal position, said frame including upper and lower horizontally extending portions constituting the inner halves of crankcases and end columns rigidly secured to said horizontal frame portions to provide a unitary rectangular shaped structure with the laterally removably cylinders disposed within the interior of said rectangle, at least one of said end columns being of hollow box-like formation in transverse section, and a gear train located in said hollow section for connecting the upper and lower crankshafts.

4. The combination in an engine comprising, a frame, upper and lower crankshafts normally mounted therein, opposed pistons connected to said crankshafts, cylinders in which said pistons operate with a common combustion chamber therefor, and means whereby said cylinders are supported by said frame and are laterally removable therefrom while both the upper and lower crankshafts remain in their normal position, each of said cylinders being formed in two coaxial halves connected together, whereby one of the cylinder halves is removable laterally while the other cylinder half is in position.

5. The combination in an engine comprising, a frame, upper and lower crankshafts normally mounted therein, opposed pistons connected to said crankshafts, cylinders in which said pistons operate with a common combustion chamber therefor, means whereby said cylinders are supported by said frame and are laterally removable therefrom while both the upper and lower crankshafts remain in their normal position, each of said cylinders being divided transversely slightly off the middle of the common combustion chamber so that one cylinder half is longer than the other, and a fuel injector mounted in the longer one of said cylinder halves for injection of fuel into the common combustion space.

6. The combination in an engine comprising, a frame, upper and lower crankshafts normally mounted therein, opposed pistons connected to said crankshafts, cylinders in which said pistons operate with a common combustion chamber therefor, and means whereby said cylinders are supported by said frame and are laterally removable therefrom while both the upper and lower crankshafts remain in their normal position, said frame having upper and lower horizontal portions integrally connected to tension plates disposed between adjacent cylinders which are laterally removable while said upper and lower frame portions and plates remain as an integral unit.

Certificate of Correction

Patent No. 2,469,651.

May 10, 1949.

CARL A. JACOBSON

It is hereby certified that error appears in the printed specification of the above numbered patent requiring correction as follows:

Column 3, line 66, claim 2, for the word "removably" read *removable*; and that the said Letters Patent should be read with this correction therein that the same may conform to the record of the case in the Patent Office.

Signed and sealed this 15th day of November, A. D. 1949.
